FIG. 13.

UNITED STATES PATENT OFFICE.

GUSTAF I. SILBERT, OF CHICAGO, ILLINOIS, ASSIGNOR TO FEDERAL ELECTRIC COMPANY, A CORPORATION OF ILLINOIS.

ADAPTER FOR ELECTRIC-LAMP SOCKETS.

1,060,953.

Specification of Letters Patent.

Patented May 6, 1913.

Application filed August 25, 1910. Serial No. 578,949.

To all whom it may concern:

Be it known that I, GUSTAF I. SILBERT, a citizen of the United States, and a resident of Chicago, in the county of Cook and 5 State of Illinois, have invented certain new and useful Improvements in Adapters for Electric-Lamp Sockets; and I do hereby declare that the following is a full, clear, and exact description thereof, reference being 10 had to the accompanying drawings, and to the letters of reference marked thereon, which form a part of this specification.

This invention relates to an adapter for electric lamp sockets provided with a switch 15 for opening and closing the circuit of the lamp of that type known as a "pull socket."

The invention consists in the matters hereinafter described and more particularly pointed out in the appended claims.

20 In the drawings:—Figure 1 is a perspective view of the improved "pull socket" adapter. Fig. 2 is a bottom plan view of the adapter. Fig. 3 is a top plan view. Fig. 4 is a vertical section through the 25 adapter on the line 4—4 of Fig. 3. Fig. 5 is a vertical section on the line 5—5 of Fig. 3. Fig. 6 is a partial vertical section through the adapter in the same plane as that of Fig. 4, but looked at from the opposite direction. Fig. 7 is a vertical section through Fig. 6 on the line 7—7 thereof. Fig. 8 is a cross-section through Fig. 7 on the line 8—8 thereof. Fig. 9 is a partial vertical section through Fig. 8 on the line 9—9 thereof. 30 Figs. 10, 11, 12 and 13 are detail perspective views of different operating parts of the switch mechanism which will be more particularly referred to in the description which follows. Fig. 14 is a view in perspective showing a part of the finishing shell. In the views shown in Figs. 1 to 5, the drawings are made to full scale, while in Figs. 6 to 14, the parts are shown on an exaggerated scale.

45 A is the body of the adapter which is preferably made of porcelain or other non-conducting material. The body is made in two parts and comprises upper and lower blocks A¹, A² which abut at their adjacent 50 ends in a horizontal plane, as indicated at a, and which are provided, respectively, with recesses a¹, a² which together form a vertical, annular chamber A^x that incloses the operating parts of the switch mechanism.

The upper block A¹ is cylindric and forms 55 the plug member of the adapter. It is inclosed by an externally threaded contact shell B adapted to fit within the wall socket. The lower block A² forms the socket member. It is a circular block of rounded cross-section and has a central annular boss on its upper end of substantially the diameter of the upper member A¹, which boss is embraced by the lower edges of the shell B.

C is an internally threaded shell contact 65 secured to the block A² for the attachment of the lamp. Said shell is provided with a horizontal flange c at its upper end which lies in an arcuate recess a³ formed in the under face of the block A².

70 D is a finishing shell surrounding the threaded contact shell C and insulated therefrom by an intermediate sleeve E of insulating material. The upper end of said shell D is embraced by an annular flange A³ 75 formed on the block A². Said flange is provided with diametrically opposed, inwardly projecting shoulders A⁴ which are adapted to engage spring metal tongues d projecting from the body of the shell D near its upper 80 edge and preferably formed by cutting strips from the body of the shell, as indicated in Fig. 14. Vertical openings A⁵ are formed through the block A² (see Fig. 5) above the shoulders A⁴ for the purpose of 85 introducing a small tool by means of which the spring tongues d may be pushed inward away from their engagement with the shoulders in order that the finishing shell may be removed. This forms a simple construction 90 for attaching the finishing shell in assembling the parts and one which provides for its ready removal for repairs or renewal.

At the upper end of the plug shell B are formed horizontal tongues b which engage 95 within recesses b¹ formed in the top of the block A¹. The block A¹ is provided with vertical grooves e on its outer surface in line with the tongues b and with vertical holes e¹ in the block A². Bolts E¹ extending 100 through said grooves and openings and through the tongues b and the flange c of the socket shell, hold the blocks A¹, A², together, support the lower contact shell C in place and serve to electrically connect the 105 two shells. A sleeve F of insulating fixer is interposed between the shell B and the block A¹. Said sleeve covers the grooves e

and also insulates the chamber A^x near its median line where its circular walls approach the engaging edges of the block.

G indicates the central contact of the socket and H the central contact of the plug.

5 The switch mechanism, by means of which the lamp circuit is opened or closed, is located between said central contacts and is adapted to make and break connection between them. The central contact G of the

10 socket projects below a boss G^1 formed on the lower face of the block A^2 and serving to insulate said central contact member from the shell flange c. Said contact G is provided with an extension g which rests in a depression g^1 to one side of the boss G^1 and is retained in place on the block A^2 by means of a screw g^2 which passes through a recess g^3 opening into the chamber A^x . In

15 20 the lower circular wall of said chamber there is embedded an arcuate contact J provided with a lateral off-set j having a screw-threaded recess to receive the threaded end of the screw g^2 , which thus retains the central contact G and the arcuate contact J in

25 place and also electrically connects them. The central contact H of the plug consists of an upset flange on a vertical tube h which is located in a recess h^1 in the upper block

30 A^1 . Said tube projects through the upper curved wall of the chamber A^x where it is provided with a bur h^2 to retain it in place. An arcuate contact K is located in the upper wall of the chamber A^x to one side of said

35 tube h and vertically above the arcuate contact J and is retained in place by means of said bur h^2 . At the opposite ends of said contact K the curved wall of the chamber is recessed to form shoulders K^1 K^2 , the purpose of which will presently appear.

40 The engaging faces of the blocks A^1 A^2 are grooved to one side of the chamber to form a central, lateral extension M of said chamber. The walls of said extension are

45 notched to receive the square head m of a bolt M^1 which has its opposite end located in grooves m^1 in the engaging faces of said blocks which together form a recess m^2 to receive the end of said bolt. Said bolt forms

50 a journal for a pulley N and a disk P which are located side by side in the chamber A^x . The disk P, (shown in perspective in Fig. 11,) is provided with a series of annularly arranged slots or openings p which are

55 adapted to be engaged by a series of similarly arranged ratchet teeth n formed on a plate n^1 which is secured to the adjacent face of the pulley N. (See Fig. 10). A coiled spring Q is mounted on the bolt M^1 and has

60 one end in fixed engagement with the pulley N and its opposite end locked between the bolt-head m and the wall of the recessed extension M. Adjacent the disk P an arm R is rotatively mounted on the bolt and is

65 provided with lugs r, r which engage within

the notches p of the disk to lock said arm to the disk when the disk is rotated in the direction of the arrow. (Said arm is shown in perspective in Fig. 12.) Pivotedly mounted at the opposite ends of said arm R are spring controlled pawls S (see Fig. 13 which is a perspective view of one of said pawls,) having arcuate flanges s which are adapted to engage the arcuate contacts J, K. A washer r^1 is interposed between the swinging arm R and the adjacent flat wall of the chamber A^x .

70 The spring Q holds the pulley with the ratchet teeth n in yielding engagement with the notches p of the disk P, so that when the pulley N is turned in one direction, said ratchet teeth engage said notches and rotate the disk P with the pulley whereas when said pulley is rotated in the opposite direction, the pulley yields away from the disk 75 to permit said teeth to pass by said notches without any effect in rotating the disk. In addition, by reason of the rigid connection of the ends of said spring, as above described, it acts as a torsional spring to return said pulley to its initial position after it has been rotated beyond that position in the operation of the switch.

80 The pawls S are pivoted to the arm R by means of short screws s^1 and are held yieldingly in engagement with the outer curved wall of the chamber A^x by means of springs s^2 which are attached at one end to lugs s^3 formed on said pawls and at the other end to lugs r^2 formed on said arm. 85 It is apparent that by reason of the engagement of the lugs r in the notches p, the rotation of the disk P in the direction of the arrow will cause the rotation of the arm R. To the pulley N is attached a cord T which is given a half turn about said pulley. Said cord passes out through an opening T^1 in the lower block A^2 which connects the chamber A^x with the space outside of said block. A horn U with a flared outer end is mounted in the outer end of said opening to reduce friction in the operation of the cord.

90 105 110 115 120 125 130 The operation of the device is as follows: When the parts of the switch are in the position indicated in the drawings, the central contacts of the plug and socket of the adapter are connected together through the arcuate contact K, the upper pawl S, the swinging arm R, the lower pawl S and the lower arcuate contact J. In this position the circuit is closed and the lamp is burning. To break the circuit the cord T is pulled downwardly. This rotates the pulley N in the direction of the arrow, which is continued until the cord has been unwound from the pulley, when the arcuate flanges s of the pawls S will have passed beyond the ends of the arcuate contacts J, K, which breaks the circuit and puts the lamp out. When the upper pawl passes be-

yond its arcuate contact, it swings outwardly about its pivotal point under the action of the springs s^2 to engage behind the shoulder K^2 , which locks it against backward rotation when the cord is released and the spring Q , acting torsionally, returns the pulley to its initial position. The disk P remains stationary, as the ratchet teeth, by reason of the yielding action of the spring, 10 slide by the openings p in said disk without effect. To turn on the light, the cord is again pulled, whereupon the pawl S which was down before, will be rotated into the upper position so as to engage behind the 15 shoulder K^1 , which locks it, upon the release of the cord, in contact with the upper arcuate contact K , with the pawl S , which was formerly in the upper position, in contact with the lower arcuate contact J . This 20 closes the circuit again and lights the lamp.

While I have shown herein certain details of mechanical construction which embody the preferred form of my improved adapter it is to be understood that these may be 25 changed and modified in various ways without departing from the spirit of my invention and I do not wish to be limited to the construction and arrangement shown herein except as pointed out in the appended 30 claims.

I claim as my invention:—

1. In an electric lamp socket, a body of insulating material inclosing a flat substantially circular chamber, arcuate contacts located on opposite sides of the peripheral wall of said chamber, one of said contacts being connected with a line terminal and the other being connected with one of the lamp 35

contacts, a non-rotatable transverse shaft fixed in said chamber walls, a pulley loosely mounted on said shaft, spring-controlled pawls carried at the ends of said arm and provided with contacts adapted for engagement with said arcuate contacts, means interposed between said arm and said pulley 40 adapted to rotate said arm when said pulley rotates in one direction but to permit said pulley to rotate freely in the opposite direction without affecting said arm, offsets formed in the peripheral wall of said chamber at the ends of one of the said arcuate contacts, against which offsets said pawls are adapted to engage to prevent backward 45 rotation of the same, and a flexible member attached at one end to said pulley and projecting at its other end through a passage 50 provided in said insulating body.

2. In a lamp fixture, in combination with a block provided with an annular face, an annular recess in its face, a metallic shell 60 fitting in said recess, longitudinal apertures in said plug radially beyond said recess, said apertures terminating in shoulders, and tongues punched in the walls of said metallic shell adapted to be forced into said 65 recess and to spring beyond the walls of said shell and engage said shoulders at the ends of said longitudinal apertures.

In testimony, that I claim the foregoing as my invention I affix my signature in the 70 presence of two witnesses, this 19th day of August A. D. 1910.

GUSTAF I. SILBERT.
